UNITED STATES PATENT OFFICE.

WILLIAM I. WHITE, OF GREENWOOD, INDIANA.

CAN-CAP-PLACING MACHINE.

No. 882,603.

Specification of Letters Patent. Patented March 24, 1908.

Application filed August 18, 1908. Serial No. 330,767.

To all whom it may concern:

Be it known that I, WILLIAM I. WHITE, a citizen of the United States, residing at Greenwood, in the county of Johnson and State of Indiana, have invented certain new and useful Improvements in Can-Cap-Placing Machines, of which the following is a specification.

The object of my invention is to provide a mechanism for automatically placing caps upon cans which have been previously filled with material to be preserved.

The accompanying drawings illustrate my invention embodied in an attachment to be placed over the feeding carrier of a can-capping machine.

Figure 1 is a plan; Fig. 2, a side elevation; Fig. 3, a vertical section of the feeding mechanism about full size; Fig. 4, a sectional detail of parts of Fig. 3 showing the positions of parts at the time when a cap is being discharged from the feed chute; Fig. 5, a similar view showing the positions assumed by the parts at completion of the discharge stroke; Fig. 6, a similar view showing the discharged cap falling to final position upon a can; and Figs. 7, 8 and 9 views similar to Figs. 4, 5 and 6 respectively, showing another form of cap and ejecting plunger.

In the drawings, 10 indicates a suitable supporting frame having a plate or table 11 in which is formed an opening 12 through which the caps are to be discharged in succession upon cans 13 carried beneath plate 11 by means of a suitable carrier 14. Arranged upon plate 11, between suitable guides 15, is a reciprocating plunger 16 provided at its forward end with a portion 17 adapted to engage the caps 18. In the present form I show the portion 17 as reduced and rounded to enter the cupped underside of the cap 18. To this plunger may be given any other suitable form for engagement with the caps without departing from my invention. Plunger 16 is normally held, by means of a spring 19, with its end 17 in position to receive a cap 18. For the purpose of reciprocating plunger 16 I journal, in frame 10 upon each side of the carrier 14, a shaft 20 which, at its upper end, is provided with an arm 21 adapted to engage a pin 22 carried by the plunger 16. Secured to each shaft 20, at a point over the carrier 14, is an arm 23 said arms projecting toward each other in position to be engaged by can 13 as it is carried beneath the plate 11, and separated so as to

rock shafts 20 and, through arms 21, project the plunger 16 toward the opening 12. Arranged above plate 11 is a guide 30 in which is mounted a vertically reciprocable guard 31 which, in the present case, is shown as tubular in form, the internal diameter being slightly greater than the diameter of the caps 18. The guard 31 normally lies upon the top of the plunger 16, either by its own weight or by reason of a suitable spring 32.

Leading to the guideway formed by guard 31 is a chute 33 in which may be placed a stack of caps 18 said stack resting upon plunger 16. The caps 18 are cupped and therefore nest one upon the other so that ordinary ejecting means cannot be used to eject the lowermost cap and it is for this purpose that the vertically yielding guard 31 is provided.

The operation of the mechanism thus far described is as follows: Referring particularly to Fig. 3, it will be noticed that the lowermost cap 18 is engaged by the forward end 17 of the plunger 16 and the lower edge of guard 31 lies low enough to prevent the next higher cap 18 from entering the mouth X between the lower edge of the guard 31 and table 11 and consequently the lower edge of the guard is nearer the table than the top of the first or lowermost cap 18. As a can is carried by carrier 14 between the arms 23 the plunger 16 is projected (as shown in Fig. 4) forward beneath the guard 31 toward opening 11 and said guard yields vertically to permit the passage of the lowermost cap 18 but at all times remaining near enough to the table 11 to prevent any ejecting movement of the next higher cap, as clearly shown in Fig. 4. Continued movement of plunger 16 carries the ejected cap to the position shown in Fig. 5 where it lies partially over the opening 12 in table 11. As the can 13 proceeds beneath plate 11 it first passes through between arms 23 so that spring 19 may return the plunger quickly to its initial position. The can then comes between the arms of star wheels 40 (only one of which is shown) carried by shafts 41 journaled in frame 10 upon opposite sides of carrier 14 and this movement of the can causes a rotation of the shafts 41 and a consequent movement of the star wheels 42 (which are similar to the star wheels 40 and similarly placed), carried by the upper ends of shafts 41 and lying immediately above table 11, and these star wheels 42 engage the ejected cap 18 and

carry it forward until it drops through opening 12. In the meantime the can 13 has advanced sufficiently to lie beneath the opening 12 in position to receive the cap as it falls through the opening as shown in Fig. 6.

In Figs. 7, 8 and 9 I show a modification which may be used to advantage with some forms of caps. In this form the forward end of the plunger 16' is cupped to fit the external circumference of the cap 18' and is slightly tapered vertically so as to pass beneath the bottom of the next higher cap.

It will, of course, be understood that instead of projecting the ejected cap 18 through the hole 12, any other suitable means may be provided without departing from my invention. A spring finger 50 is projected over opening 12 so as to insure the passage of the caps through the opening.

20 I claim as my invention:

1. The combination, with a feeding table, of a cap-holding tube arranged over the table and movable toward and from the table, a cap ejecting member adapted to engage the interior of the initial cap, and means for driving the ejecting member beneath the said tube.

30 2. The combination, with a feeding table, of a cap-holding tube arranged over the table and movable toward and from the table, a cap-ejecting plunger, means for carrying cans successively beneath the table, means operated by the cans for operating the plunger, and means operated by the cans for depositing ejected caps upon the cans.

35 3. The combination, with a feeding table, of means for carrying cans in succession beneath said table, a cap-holding tube arranged above the table and movable toward and from the table, a plunger mounted on the table and adapted to be projected beneath said tube, a portion of said plunger lying initially beneath the tube and adapted to enter the cupped under-side of the lowermost 40 cap, means operated by the cans for reciprocating said plunger, and means operated by the cans for shoving the ejected caps from the table and depositing them upon the cans.

45 4. The combination, with a feeding table,

of means for carrying cans in succession beneath said table, a cap-holding tube arranged above the table and movable toward and from the table, a plunger mounted on the table and adapted to be projected beneath said tube, means operated by the cans for reciprocating said plunger, and means operated by the cans for shoving the ejected caps from the table and depositing them upon the cans.

5. The combination, with means for holding a series of nested cupped elements in a stack, which means comprises a guard yieldingly movable axially of the stack and engaging two or more of the cupped elements thereof, of ejecting means movable transversely of the line of movement of said yielding guard and adapted to engage the interior of the initial element of the stack and project the same beneath the guard.

6. The combination, with means for holding a series of can caps in an axial stack, means for ejecting said caps successively therefrom, a guard forming a part of the stack forming means and arranged to co-operate with said ejecting means and yieldingly in the line of thickness of the caps, means for feeding cans in succession to cap-receiving position, and means operated by the cans for depositing the ejected caps upon the cans.

7. The combination, with means for forming an axial stack of cupped elements, of an ejecting means adapted to traverse the axis of the stack and to engage the interior of the under cupped portion of the initial element to project the same transversely of the stack, and means for engaging the remaining elements of the stack and holding the same against transverse displacement.

In witness whereof, I, have hereunto set my hand and seal at Indianapolis, Indiana, this 31st day of July, A. D. one thousand nine hundred and six.

WILLIAM I. WHITE. [L. s.]

Witnesses:

ARTHUR M. HOOD,
THOMAS W. MCMEANS.
